UNITED STATES PATENT OFFICE.

COLEMAN FINLEY, OF DUDLEY, ILLINOIS.

CAN-OPENER.

1,341,421.

Specification of Letters Patent.

Patented May 25, 1920.

Application filed January 2, 1920. Serial No. 348,792.

To all whom it may concern:

Be it known that I, COLEMAN FINLEY, a citizen of the United States, residing at Dudley, in the county of Edgar and State 5 of Illinois, have invented certain new and useful Improvements in Can-Openers, of which the following is a specification.

This invention relates to can openers, and has for its object to provide an improved 10 can opener which can be used either to cut through the top of a can, or to cut through the side wall of a can near the top, whereby it is adapted for use on cans of various kinds. The cutting member of the tool is 15 adjustable so that it can be used on cans of various diameters.

The device is illustrated in the accompanying drawing in which Figure 1 is a perspective view. Fig. 2 is a side elevation. The 20 tool comprises a handle member and a cutting member adjustably mounted thereon. The handle comprises a loop 6 conveniently made of heavy wire, each branch terminating in a point 7 which is offset angularly 25 as indicated at 8 from two bends 9 where the branches of the wire loop are secured together by band 10 or the like. Either of the points 7 is adapted to be punched through the top of a can at the center there- 30 of to bring the cranked part 8 into position as a pivot on which the tool may be turned around the can.

The two branches of the handle are parallel, and the cutter is slidably mounted on 35 these branches. This cutter comprises a strip of metal folded upon itself to form two bends 11 and 12 with parallel parts 13 having holes in line with each other through which holes the branches of the handle 6 ex- 40 tend. One end of this cutting member is presented on one side of the handle perpendicularly to the axis thereof, as indicated

at 14, this end being tapered to a point with sharpened edges. The other end of the cutting member is bent as indicated at 15 45 into parallelism with the axis of the handle, and sharpened to a point at 16 which is presented forwardly as shown.

In the use of the device, if it is desired to cut through the top of the can, the proper 50 point 7 is punched through said top, and the point 14 is then punched through the top near the outer edge thereof, and then by turning the tool said point 14 cuts a circle 55 through said top. For cutting off the upper end of a can the other point 7 is punched through the top and the point 16 is then punched through the side wall of the can, and then by turning the handle the side wall 60 is cut around to detach the upper part of the can. The cutting member can be slid in or out on the handle to accommodate the 65 blades to cans of various sizes, and the tool can be cheaply constructed and will be found convenient for the intended uses. 65

I claim:—

A can opener comprising a handle consisting of a loop with forwardly extending branches each of which ends in an offset point adapted to be inserted through the 70 top of a can, and a cutter member consisting of a folded piece of metal through which the branches of the handle extend, said member terminating in blades at its opposite ends, one blade being presented at an angle 75 to the axis of the handle and the other parallel thereto.

In testimony whereof, I hereby affix my signature in presence of two witnesses.

COLEMAN FINLEY.

Witnesses:

ELSIE BENNETT,
JOHN H. HANNA.
